T. S. FRIEND

CAN

Filed Sept. 26, 1922

INVENTOR:

Thomas S. Friend
By Glenn S. Noble
ATTY

UNITED STATES PATENT OFFICE.

THOMAS S. FRIEND, OF CHICAGO, ILLINOIS.

CAN.

Application filed September 26, 1922. Serial No. 590,574.

To all whom it may concern:

Be it known that I, THOMAS S. FRIEND, a citizen of the United States, residing at Chicago, in the county of Cook and State 5 of Illinois, have invented certain new and useful Improvements in Cans, of which the following is a specification.

This invention relates more particularly to vessels or receptacles adapted to receive 10 waste material such as used paper towels, rags, oily waste and also for laundry and other similar purposes.

The objects of this invention are, to provide a can or receptacle of this character 15 which will be of simple construction and practical in operation; to provide a can having a self-closing door which will be substantially water tight and which will not be apt to be affected by the air; to provide 20 a receptacle for oily waste which will be ventilated and which will tend to confine any combustion in the can; to provide a can of this character into which the waste material may be easily deposited; and in general 25 to provide such improvements and novel features as will be described more fully hereinafter.

In the accompanying drawings illustrating this invention;

Figure 1 is a front view with parts broken away to show the interior construction; and

Figure 2 is a sectional view taken on the line 2—2 of Figure 1.

The can or receptacle 3 is preferably made 30 rectangular or square in cross section and of any suitable size. The can may also be made of any suitable material but preferably of sheet steel, galvanized iron or the like. The can may set directly on the floor or may be provided with legs 4 for supporting the same above the floor which is desirable in case it is to be used for oily waste or material which may be apt to get on fire.

The can is provided with a top or cover 5 having a depending flange 6 which extends well down over the upper end of the can. The can cover may be held in position by any suitable means such as ears 7 which extend up through slots or holes 8 in the top and are provided with holes 9 for receiving the fasteners 10. These fasteners may be conveniently held by chains 11 to prevent their being lost. It will also be noted that padlocks may be substituted for

the fasteners if it is desired to lock the cover in position.

The cover 5 has an opening 12 for receiving the material and this opening is covered by a cap or housing 13 having a self-closing door 14 at the front thereof. In the particular arrangement shown the housing has triangular ends 15 and a sloping roof 16. The door 14 is carried on a rod 17 which passes through a bead 18 along the upper edge of the door and is mounted in bearings 19 in the sides 15. The ends of this rod are preferably provided with nuts 20 for holding the same in position. The lower end of the door strikes against an abutment 21 along the front edge of the opening 12 and the sides overlap flanges 22 which extend inwardly from the sides 15, thus making a substantially tight closure and permitting the door to be made sufficiently short so that it will not bind on the sides. It will be noted that the bearing or hinge for the door is in advance of the stop at the bottom, so that the door will swing to closed position by gravity and the lower edge of the door may be provided with an additional weight 23 to make the closing more positive.

It is desirable to ventilate cans which are intended to be used for oily waste or material which may be subject to spontaneous combustion and heretofore this has commonly been done by providing holes in the top of the can. This, however, is objectionable as these holes may become clogged when the can is filled and also furnish passageways for the flames in the event of fire in the can. In the present instance I provide such ventilation in the housing 13 by making one or more holes 24 in the sides 15. When additional protection is desired, these holes may be covered with fine screens 25 which will prevent the egress of the flames. These screens may be conveniently held in frames 26 which are riveted to the sides by means of rivets 27 so that they will not be apt to be affected by the heat as would be the case if they were soldered in position.

From this description it will be seen that I provide a can for collecting waste which is adapted for either inside or outside use and which will positively retain the material placed therein as well as protect it from the elements. Furthermore, the material to be deposited in the cans may be very readily

inserted and the door will always return to closed position. Furthermore, on account of the door swinging back over the ventilating holes it will not be possible to cover 5 the holes with the material placed in the can.

It will be noted that various changes may be made in the details of construction and arrangement of the parts in order to adapt the receptacle to different conditions or uses, 10 and therefore I do not wish to be limited to the exact construction herein shown and described, except as pointed out in the following claims.

I claim:

- 15 1. A receptacle of the character set forth having a removable cover with an inlet housing extending upwardly from the cover said housing having triangular ends, both of the upwardly extending sides of the triangles 20 being pitched backwardly in the same direction from a vertical plane whereby the roof and the front portion of the housing will be sloped in the same direction, said front portion having an inlet opening and a self-closing 25 door in said housing for covering said opening, the arrangement being such that the door when in normally closed position will be at an acute angle to the perpendicular.
- 30 2. A can for waste material or the like having an inlet housing extending upwardly from the top thereof with a swinging door in one side, said door being mounted so that it closes by gravity and when closed 35 will have its upper pivoted end extending outwardly from the lower edge.
3. The combination with a receptacle, of

a cover having an opening therein, a housing over said opening, said housing having triangular sides, and a sloping roof, a rod 40 pivotally mounted in the upper portions of the sides, a door mounted on said rod and adapted to engage with the edge of the cover along the forward side of the opening, flanges for engagement with the sides of the 45 door, the door being mounted so that the pivot is in advance of the stop at the bottom whereby the door is normally in a slanting position.

4. The combination of a rectangular can 50 having ears projecting upwardly from the sides thereof, a cover for said can having slots for receiving the ears, fasteners for engaging with said ears, a housing projecting upwardly from said cover, and a swinging 55 door in front of the housing, said door being mounted so that it will close by gravity.

5. The combination with a can for waste material, of a cover, and having a sloping front with a door opening therein, a flat 60 door for said opening pivoted at the top with the pivot in advance of the stop in the bottom of the front whereby the door will close tightly under the action of gravity, an inlet housing projecting upwardly from the 65 cover and ventilating openings in the sides of said housing.

6. A can for waste or the like having a cover with an upwardly projecting housing with a flat door in the front thereof adapted 70 to close against a sloping frame in the housing, openings in the sides of said housing and screens covering said openings.

THOMAS S. FRIEND.
